(57) **CLAIM**

The ornamental design for a belt, as shown and described.

DESCRIPTION

FIG. 1 is a front perspective view of a belt, showing my new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a partial enlarged view of FIG. 1;

FIG. 10 is a partial enlarged view of FIG. 2;

FIG. 11 is a partial enlarged view of FIG. 2;

FIG. 12 is a partial enlarged view of FIG. 7;

FIG. 13 is a partial enlarged view of FIG. 7;

FIG. 14 is a front perspective view of the belt in an opened state; and,

FIG. 15 is a rear perspective view of the belt in an opened state.

The dashed broken lines in the figures are for the purposes of illustrating portions of the belt and form no part of the claimed design.

The dash-dot-dash broken are for notating enlarged views and form no part of the claimed design.

1 Claim, 11 Drawing Sheets
